(57) **CLAIM**

The ornamental design for a capillary mounting clip, as shown and described.

DESCRIPTION

FIG. 1 illustrates a front top perspective view of an ornamental design for a capillary mounting clip;

FIG. 2 illustrates a bottom rear perspective view of the ornamental capillary mounting clip shown design in FIG. 1;

FIG. 3 illustrates front view of the ornamental capillary mounting clip design shown in FIG. 1; and,

FIG. 4 illustrates rear view of the ornamental capillary mounting clip design shown in FIG. 1.

The broken lines showing portions of the mounting clip, a portion of the capillary tube and openings are for the purposes of illustrating environmental structure and form no part of the claimed design.
